UNITED STATES PATENT OFFICE.

JOSEPH J. KRAMER, OF NEW YORK, N. Y.

SAFETY PIN.

Application filed July 17, 1925. Serial No. 44,271.

This invention relates to safety pins and more particularly to a novel and improved means for locking the pointed or movable member in the hood or shield so as to prevent piercing the surrounding area which may occur when the pin is accidentally opened.

One of the objects of my invention is to provide a safety pin wherein the back or 10 fixed member is provided with a slidable latch or lock, adapted to cooperate with the hood or shield of the safety pin so as to prevent the pointed or movable member of the pin from becoming disengaged from the said 15 hood or shield and opened.

To enable others skilled in the art to fully comprehend the underlying features of my invention that they may embody the same in the various alterations in structure and 20 re-lations contemplated, drawings depicting a preferred form have been annexed as a part of this disclosure and in such drawings, similar reference characters denote corresponding parts throughout all the views, of 25 which,

Figure 1 is a side view of the safety pin showing the same when closed and the pointed or movable member locked.

Figure 2 is a similar view, showing the 30 pointed or movable member open and the lock or latch disengaged from the hood or shield.

Figure 3 is a sectional view, taken on the line 3—3 of Figure 1.

Figure 4 is a sectional view taken on the 35 line 4—4 of Figure 1.

Figure 5 is a sectional view taken substantially on the line 5—5 of Figure 1.

Figure 6 is an end view of the lock or 40 catch.

Referring now to the drawings, wherein like reference characters designate corresponding parts throughout the several views, 45 5 designates the back or fixed member and 6 the pointed or movable member, preferably formed integral with each other and joined by the usual coiled spring 7. The back or fixed member is provided with the usual type of head 8 and hood or shield 9, adapted to 50 receive the pointed end of the movable member above referred to.

My invention proper consists of a slidable lock or catch formed from a single blank and having slats 10, 11, formed integral 55 with a sleeve 12, whereby the lock or catch

may slide on the upper portion of the back or fixed member. The said wings are preferably riveted as at 13, the front edges of said wings being bent outwardly or slightly flared as indicated at 14 so as to engage the 60 edge of the movable member 6 when in its locked position. The top of the lock or latch is also open so as to bridge the hood or shield, in which position it also engages the pointed or movable member and prevents 65 its separation when locked as shown by Figure 1 of the drawings. In order to prevent the lock or latch from moving toward the coiled spring, the back or fixed member is preferably flattened slightly, as indicated at 70 16, thus producing a stop so as to limit the movement thereof. The lock or latch is loosely mounted on the back or fixed member 5 and it will thus be seen that it may rotate relative to the back or fixed member 75 when in its disengaged position so that the said lock or latch will not interfere with the movement of the pointed or movable member when it is being directed into the hood or shield.

It will readily be seen that the lock or latch is in engagement with the hood or shield as well as with the pointed or movable member and that the latter cannot be moved either to the left or right to be disengaged from the hood or shield and in which position it securely retains the movable member in its properly locked position.

While I have illustrated and described my invention with some degree of particularity, 90 I realize that in practice, various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. A safety pin having a latch or lock comprising a pair of connected wings movable along the back of the said pin and adapted to interlock with the safety pin 105 sheath and engage the pointed end of said pin when in said sheath, and means formed in the back of said pin for limiting the movement of said pin lock.

2. A safety pin having a latch or lock 110

comprising two connected resilient wings formed from a single blank and movable along the back of the said pin, said wings being spaced to yieldably interlock with the safety pin sheath and engage the pointed end of said pin when in said sheath.

3. A safety pin having a latch or lock comprising two connected wings formed from a single blank and movable along the back of the said pin, a stop for said latch or lock, said wings being spaced to interlock with the safety pin sheath, the front edges of said wings being slightly flared to engage

the pointed end of said pin when in said sheath. 15

4. A safety pin having a latch or lock comprising two similarly shaped wings formed from a single blank and riveted together for movement on the back of said pin, a stop for said latch or lock, said wings being spaced to interlock with the safety pin sheath, the front edges of the wings being bent outwardly to engage the pointed end of said pin when held in the said sheath. 20

In testimony whereof I affix my signature.

JOSEPH J. KRAMER.
